TOUPEE COMB

R. Glenn Herrin, Rte. 3, Box 81,
Oliver Springs, Tenn. 37840

Filed May 21, 1973, Ser. No. 362,045

Term of patent 14 years

Int. Cl. D28—03

U.S. Cl. D86—8

Fig. 1.

Fig. 2.

Fig. 3.

Fig. 4

Fig. 5

FIG. 1 is a side elevational view of the toupee comb, the opposite side being a mirror image thereof, showing my new design.

FIG. 2 is a top plan view thereof.

FIG. 3 is a right end elevational view thereof.

FIG. 4 is a left end elevational view thereof.

FIG. 5 is a bottom plan view thereof.

I claim:

The ornamental design for a toupee comb, substantially as shown and described.
